UNITED STATES PATENT OFFICE.

VERNON J. PRICE, OF DETROIT, MICHIGAN.

SAFETY DEVICE FOR BANKS.

Application filed March 24, 1921. Serial No. 455,034.

To all whom it may concern:

Be it known that I, VERNON J. PRICE, a citizen of the United States, residing at Detroit, county of Wayne, State of Michigan,

5 have invented a certain new and useful Improvement in Safety Devices for Banks, and declare the following to be a full, clear, and exact description of the same, such as will enable others skilled in the art to which it 10 pertains to make and use the same, reference being had to the accompanying drawings, which form a part of this specification.

My invention relates to a safety device for banks and its principal object is to provide 15 an instantly actuated bullet proof metallic screen adapted to form a barricade in front of the several "bank cages" to protect the clerks against the attack of hold-up-men should an attempt be made by the latter to 20 rob the bank.

A further object of the invention is to provide means for simultaneously and automatically locking the several exits or other doors of the bank, upon the release of the 25 protecting screen and to simultaneously sound an alarm outside the bank and at police headquarters that the robbers may be trapped in the bank until the arrival of the police.

30 A further object is to provide means for releasing the door or doors to admit the police without lowering the protecting screens.

A further object is to provide slidable windows in the teller's cage formed of bullet 35 proof glass adapted to be raised from the inside only to admit grips or relatively large packages containing securities or deposits.

A further object is to provide a slidable tray to receive the pass book and deposit 40 of the customer which is adapted to be pushed through a slot in the wall of the teller's desk from the outer office or vice versa,—the construction being such that the slot through which the tray passes is closed 45 by the walls of the latter at each alternate movement of the tray.

With the foregoing and other objects in view which will appear as the description proceeds the invention further resides in 50 the combination and arrangement of parts and in the details of construction hereinafter described and claimed, it being understood

that changes may be made in the precise embodiment of the invention herein disclosed without departing from the spirit of 55 the same.

In the accompanying drawings: Figure 1 is an elevation of the partition dividing the teller's cage from the outer banking offices as viewed from the teller's side; showing diagrammatically a barricade screen,—means for actuating and releasing the screen,—and means for locking the exit doors of the bank.

Figure 2 is a cross-sectional view through the partition showing diagrammatically 65 means for actuating and releasing the barricade screen,—and means for automatically sounding an alarm when the screen is released.

Figure 3 is a detail sectional view through the barricade screen showing diagrammatically a switch adapted to automatically close an electric circuit for sounding an alarm outside the bank, or at police headquarters 70 simultaneously with the raising of the barricade screen.

Figure 4 is a similar diagrammatic view showing the electric circuit closed through the switch.

Figure 5 is a fragmentary elevation of the glass partition and window of a teller's cage.

Figure 6 is a horizontal cross sectional view through the partition on or about line 6—6 of Fig. 5.

Figure 7 is a vertical cross-sectional view of the glass partition taken on or about line 7—7 of Figure 5.

Figure 8 is a vertical cross-sectional view through the "talking aperture" in the glass partition taken on or about line 8—8 of Figure 5.

Figure 9 is a fragmentary elevation of one of the lazy tongs employed to raise the barricade screen showing the connection between the jointed bars of the lazy-tongs and the compressed air cylinders which serve to actuate the same.

Figure 10 is a cross-sectional detail view taken on or about line 10—10 of Figure 9.

Figure 11 is a longitudinal sectional view 100 through one of the compressed air cylinders.

Figure 12 is a cross-sectional view taken on or about line 12—12 of Figure 11.

Figure 13 is a longitudinal sectional view through the controller valve.

Figure 14 is a cross-sectional view through the controller valve on or about line 14—14 5 of Figure 13.

Figure 15 is a sectional view through the pneumatically operated bolt and its keeper.

Referring now to the letters of reference placed upon the drawings.

- 10 A, denotes a partition wall separating the usual teller's cage from the outer office of a bank or similar business office. B, indicates the teller's desk or counter and C the usual glass partition extending upwardly above 15 the counter to separate the customers from the employees of the bank. D, denotes a plurality of bullet proof metallic screens located back of the partition and in front of the teller's desk adapted when raised to provide a barricade between the outer office and 20 the teller's cage.

- E, E, indicate a plurality of jointed bars, or lazy tongs, connected preferably in pairs with the respective sections of the barricade 25 screen. F, F, denotes a plurality of compressed air cylinders arranged in pairs in opposing relation fitted with pistons F' from which extend piston rods F², connected by transverse pins f, with the downwardly 30 projecting arms E' of the lazy-tongs. The transverse pins f, extend through slotted guide plates G, bolted to the floor or other support. To limit the upward thrust of the lazy-tongs, links E², E², are provided, shown 35 in Figure 9 of the drawings. Links E³, E³ pivoted respectively to the bars E' E' and to the bracket E⁴—in turn bolted either to the guide plates G, or to the floor—are also provided to assist in limiting the upward 40 thrust of the lazy-tongs and to support the latter when raised.

- To supply the cylinders with compressed air a storage tank H is provided located in the basement of the building or other convenient place,—the air being compressed by a suitable pump I, which may be operated either by an electric motor or other source of power. I² is a pipe leading from the compressor or pump to the tank, and I³ 45 is a pipe leading from the compression tank to a manifold I⁴, preferably extending throughout the length of the tellers' cages. J, J, denote a plurality of air control valves, one or more being located in each cage and when operated by the teller or other clerk serves to release the air from the manifold I⁴ into the manifold I⁵, in turn connected by pipes I⁶ with the respective cylinders F to actuate the pistons F' and 50 thereby the lazy-tongs to lift the screens D. I⁷ are manifolds into which air is delivered from the pipe I⁵ for delivery to the adjacent compressed cylinders F, F.

- I⁸ denote a plurality of pressure gauges 65 located in convenient positions whereby the

tellers or other employees may determine at all times if the air in the manifold is under sufficient compression to actuate the barricade screens D. The valve J, for controlling the delivery of air may be of any convenient type but I prefer to employ a piston valve as indicated in Figures 13 and 14 of the drawings. J¹ is the valve casing secured to a suitable support. J² is a piston fitted at each end with suitable packing rings J³. 75 J⁴ is a piston rod fitted with a relatively long cross arm J⁵ that it may be readily operated by the teller without shifting his position upon pressing his knee against the bar. J⁶ indicates the air inlet port into the valve cylinder, and J⁷ the port through which air is delivered to the manifold I⁵ and pipe I⁶ leading to the compressed air cylinders. J⁸ is the exhaust pipe of the valve chamber. 85

To provide for the release of air which may leak past the piston rings and thus serve to prevent the free movement of the piston or plunger J²—exhaust ports J⁹ are provided through each end of the cylinder 90 wall. As shown in Figures 13 and 14, the central portion of the cylinder is provided with an annular grating wall that it may guide the piston, the slotted openings between the spaced bars providing a passage 95 for air from the inlet port J⁶ to the port J⁷ leading to the compressed air cylinder F when the piston valve J² is manually shifted to the left-hand end of the valve cylinder. When the piston is moved to the right—see 100 Figure 14—the air will pass through the port J⁷ and exhaust through the port J⁸.

K, denotes diagrammatically a revolving exit or inlet door for the bank such as are commonly used in public buildings. N, denotes a series of pneumatically operated bolts—hereafter more particularly described—adapted to engage the several blades of the door to secure the door against rotation. L is a pipe connecting the manifold I⁵ with the bolts N. 105

M, is a three way valve provided with an exhaust port M' adapted when manually rotated by the controller M^a to release the air between the valve and the bolts that the door may be opened to admit the police, and to close against the release of air from the manifold I⁵ that the protecting screens D may not descend when the exit doors are released. The bolt N is fitted with a plunger N' adapted to be projected into a keeper N² secured to the respective blades of the door. N³ is an air inlet in the wall of the bolt casing, to which the pipe L is connected. N⁴ is a spring coiled around the plunger N' 115 adapted to retract the latter upon the air being exhausted from the opposite end of the chamber. N⁵ is a plug screwed in the wall of the casing upon removing which a threaded rod may be screwed into the tapped end 120 125

N⁶ of the plunger, to provide for its forcible withdrawal from the keeper, should it become bound through any cause. P, indicates an electric switch diagrammatically shown in Figures 2, 3 and 4 of the drawings. P' is the electric circuit controlled by the switch and P² is an electric battery or other source of electrical energy. P³ indicates one or more signal bells which may be located outside the bank, or at police headquarters or both. The bullet proof metallic screens D when in their lowermost position, serve to open the switch P;—upon the screens being raised the switch will automatically close (see Fig. 4) the circuit through the source of electrical supply P² to the bell or bells.

Q are dash-pots attached to the upper rail of the partition, having projecting plungers adapted to relieve the shock due to the impact of the screens when upwardly projected. R, is a wire adapted to carry a high tension current supported by suitable insulators along the top of the partition; the wire may be continuously charged. S, denotes a series of outwardly extending barbs designed to prevent anyone from scaling the top of the partition. T, indicates a slidable tray adapted to be pushed beyond the glass partition to receive the deposit pass book or other memorandum of the customer, and when pushed inwardly the deposit may be removed by the teller and the book returned; the wall of the tray serving to close the opening between the outer office and the teller's cage as the tray is alternately pushed back and forth. U, indicates an opening in the bullet-proof glass of the teller's cage fitted with a slidable window U', supported in a suitable frame U², provided with apertures U³, to receive the ends of a pair of laterally movable bolts U⁴, U⁴, forced in opposite directions by means of a spring U⁵. U⁶ are thumb pieces secured to the bolts whereby they may be released from the apertures of the frame U², against the action of the spring. The window U' may be lowered to completely close the opening or not as desired. So also other means may be employed to support the window in its elevated position, however the construction shown is considered desirable and convenient. V, denotes an opening through which the customer may talk to the teller or vice versa and this opening may be unobstructed or a plate of laminated bullet proof glass V', may be located in front of the opening but spaced therefrom as indicated at V² for the passage of sound.

Having indicated the several parts by reference letters the construction and operation of the device will be now more fully explained.

Should anyone attempt to hold up the teller or other employee of the bank any of the employees may instantly release the me-

tallic screens D, by shifting the position of the plunger in the valve J so that it may admit air from the compression tank into the manifold I⁵ and thence to the compression cylinders E, the operation of which will 70 actuate the several lazy-tongs and thereby project upwardly the several barricade screens D between the outer and inner banking offices. The force or impact due to the rapid upward movement of the screens being relieved by the action of the dash-pots Q, as will be readily understood. It will also be noted that the link connections E², E² and E³, E³ engaging the lazy-tongs will serve to limit the movement of the latter. Simultaneous with the upward movement of the screens the plungers of the locks on the several exit doors will be thrown, thereby trapping the robbers until the arrival of the police,—the latter being simultaneously notified 80 through the synchronously operated alarm at police headquarters and upon the outside of the building. Upon the arrival of the police, the bolts engaging the doors may be released for their admission by manually operating the valve M, the air between the valve and the door bolts being thus exhausted 90 ed that the springs N⁴ may retract the bolts.

When it is desired to lower the screens D to their normal position the air under compression between the cylinders F and the control valves J is exhausted through the port J⁶, by manually shifting the piston J⁷,—the screens thereupon will descend by gravity to their initial position that they 100 may be again operated when required.

By providing pressure gauges at intervals throughout the length of the air delivery manifold the employees of the banking office will be able to determine at all times if the 105 device is in proper working condition.

It will also be understood that the operation of any one of the control valves J will serve to actuate all of the screens, thus if certain of the employees of the bank are prevented from operating the valve nearest to them or are unaware of impending danger—other employees even though remotely situated may actuate the screens by means of the control valve nearest to them.

By providing a wire at the top of the partition dividing the outer office from the tellers' cages, carrying a high tension circuit the employees are protected from anyone attempting to scale the partition to 120 threaten the lives of the clerks or to rob the bank.

Having thus described my invention what I claim is:

1. In a safety device for banks of the 125 character described provided with a front partition having a solid lower portion, a screen normally located at the solid lower portion of the partition and reciprocable vertically to cover or barricade the upper 130

portion of the partition and to uncover same, lazy-tongs having one end connected with said screen, a plurality of cylinders, a piston and piston rod for each cylinder, the 5 lower links of the other end of the lazy-tongs being pivotally connected to the piston rods, an air tank, means for delivering air from the tank to the cylinders and means controlling the delivery of air between the 10 tank and the cylinders.

2. In a safety device for banks of the character described, provided with a front partition having a solid lower portion, a metallic screen normally located at the solid 15 lower portion of the partition and reciprocatable vertically to cover or barricade the upper portion of the partition and to uncover the same, a plurality of lazy-tongs connected with the screen, a plurality of cylinders operably connected with the lazy-tongs, a stationary member, links connecting the stationary member to the lazy-tongs, for limiting the movement of the lazy-tongs, 20 an air tank, means for delivering air under pressure to said tank, means for delivering air from the tank to said cylinders, and a manually operated valve for controlling the 25 delivery of air between the tank and cylinders.

3. In a safety device for banks of the character described, a partition wall having a solid lower portion, a metallic screen normally located adjacent to the lower solid portion of the wall and reciprocatable vertically to cover or barricade the upper portion 35 of the partition and to uncover the same, a plurality of lazy-tongs connected with said screen, a plurality of air cylinders operably connected with said lazy- 40 tongs, an air tank, means for maintaining air under pressure in said tank, means for delivering air from the tank to said cylinders to actuate the screen, a piston valve adapted to control the delivery of air between the tank and cylinders, and a dash- 45 pot adapted to be engaged by the screens when near the end of their upward movement for cushioning the impact of said screens when raised.

4. In a safety device for banks of the character described, provided with a partition having a solid lower portion, a metallic screen normally located at the solid lower portion of the partition and reciprocatable vertically to cover or barricade the upper portion of the partition and to uncover the same, a plurality of cylinders, means for connecting the metallic screen with the pistons of said cylinders, a compressed air tank, 55 means for delivering air under pressure into 60

said tank, a manifold, suitable piping connecting the tank with the manifold, a second manifold, means for delivering air from the first to the second manifold, a plurality of manually operated valves severally adapted to control the delivery of air to the second manifold, and piping connecting the second manifold with the cylinders. 65

5. In a safety device for banks of the character described, provided with a partition having a solid lower portion, a metallic screen reciprocatable vertically to cover or barricade the upper portion of the partition and to uncover the same, a plurality of cylinders, means for connecting the screen with the pistons of said cylinders, an exit door, a pneumatically operated bolt adapted to secure said door, a storage tank, suitable piping adapted to deliver air to said cylinders and to the bolt, a manually operated valve for controlling the delivery of air to said cylinder and bolt, a second valve adapted to release the air controlling the operation of the bolt while holding air maintaining the pistons of the cylinder under compression, and means for automatically releasing said bolt upon exhausting the air employed to actuate the bolt. 70

6. In a safety device for banks of the character described, provided with a partition having a solid lower portion, a metallic screen reciprocatable vertically to cover or barricade the upper portion of the partition and to uncover the same, a plurality of cylinders, means for connecting the metallic screen with the pistons of said cylinders, a compressed air tank, means for delivering air under pressure into said tank, a manifold, suitable piping connecting the tank with the manifold, a second manifold, piping connecting the first manifold with the second manifold, a plurality of manually operated valves severally adapted to control the delivery of air to the second manifold, piping connecting the second manifold with the cylinders, exit doors, a plurality of pneumatically operated bolts adapted to secure said doors, a pipe connection between the second manifold and said bolts and a valve adapted to exhaust the air between the valve and the bolts, to release the exit doors and to close against the escape of air from the manifold, whereby the screen may be maintained in its elevated position. 95

In testimony whereof, I sign this specification in the presence of two witnesses.

VERNON J. PRICE.
